UNITED STATES PATENT OFFICE

158,530

GARMENT HANGER

Edith D. Tobin, Philadelphia, Pa.

Application June 13, 1949, Serial No. 3,235

Term of patent 14 years

(Cl. D80—8)

To all whom it may concern:

Be it known that I, Edith D. Tobin, a citizen of the United States of America, residing at Philadelphia, in the county of Philadelphia and State of Pennsylvania, have invented a new, original, and ornamental Design for a Garment Hanger, of which the following is a specification, reference being had to the accompanying drawing, forming a part thereof.

In the drawing:

I claim:

The ornamental design for a garment hanger, as shown.

EDITH D. TOBIN.
